UNITED STATES PATENT OFFICE.

JAMES H. DEAN, OF CHICAGO, ILLINOIS, ASSIGNOR TO COLE MANUFACTURING COMPANY, OF CHICAGO, ILLINOIS, A CORPORATION.

DRAFT ATTACHMENT FOR STOVES.

1,327,988.

Specification of Letters Patent. Patented Jan. 13, 1920.

Application filed August 30, 1919. Serial No. 320,845.

To all whom it may concern:

Be it known that I, JAMES H. DEAN, a citizen of the United States, and a resident of Chicago, county of Cook, and State of Illinois, have invented certain new and useful Improvements in Draft Attachments for Stoves, of which the following is a specification.

The invention relates to draft devices for stoves and seeks to provide simple and effective means by which heated air can be directed downwardly onto the burning material in the fire box or combustion chamber of the stove to thereby increase combustion and also by which air can be delivered upwardly into the smoke pipe of the stove to check or decrease the draft. The invention consists in the features of improvement hereinafter set forth, illustrated in the preferred form in the accompanying drawings and more particularly pointed out in the appended claims.

In the drawings, Figure 1 is a vertical section through a stove with the improved draft attachment applied thereto. Fig. 2 is a vertical, detail section on the line 2—2 of Fig. 1. Fig. 3 is a horizontal section on the line 3—3 of Fig. 2.

The stove may be of any usual or suitable construction. The form shown comprises a casing 1 mounted on a suitable base 2 and provided with a fire box 3, ash pit 5 and doors 6 and 7 opening, respectively, into the combustion chamber and ash pit of the stove, the door 7 being provided with a sliding damper 8 for regulating the admission of air to the ash pit beneath the fire box. The upper rear portion of the stove is provided with a collar 9 which engages the lower end of a suitable smoke pipe 10.

The improved draft attachment is mounted in the upper rear portion of the stove casing and comprises a flue casing 11 which is preferably U-shaped in cross section and is secured in vertical position to the inner face of the back wall of the stove casing, and the latter is provided with an air inlet or opening 12 over which the central portion of the flue casing extends. The U-shaped flue casing is preferably formed of sheet metal and is provided at its edges with flanges 13 by which it is attached, by means of bolts or rivets 14, to the stove casing.

The upper open end of the flue casing 11 terminates within the smoke pipe collar 9

and its lower open end terminates somewhat above the fire box 3, and these open ends of the flue casing form air outlets which communicate, respectively, with the smoke pipe and combustion chamber of the stove. 60 The flue casing is divided into upper and lower flue portions 15 and 16, preferably by means of a valve 17, which also controls the admission of air to either of the flue portions. 65

In the preferred construction shown, the valve 17 is cylindrical or cup-shaped and its open outer end is in communication with the air inlet 12. Preferably, as shown, the cylindrical valve extends through the air inlet 70 12 and fits between the side walls of the flue casing 11, the latter being provided with curved portions or seats 18 for the valve. At its outer end the valve is provided with a peripheral flange 19 which overlaps the 75 outer face of the stove casing 1 and the closed inner end of the valve is provided with a pintle 20 which rotatably engages a suitable opening in the inner wall of the flue casing 11. A pin 21 extends through 80 the pintle and serves to hold the rotatable cylindrical valve in position. The peripheral wall of the cylindrical valve is provided with a port 22 and by rotating the valve, the port may be brought into register either 85 with the upwardly directed flue portion 15 or with the downwardly directed flue portion 16 of the casing 11. For convenience in rotating the valve, the flange 19 thereof is preferably provided with finger pieces 90 or lugs 23.

The port 22 is of such size that by rotating the valve it may be brought into register with either one of the curved seats 18, so that both the upwardly directed flue 95 portion 15 and the downwardly directed flue portion 16 are closed. By shifting the valve to bring the port into line with either flue portion, air may be directed therethrough while the other flue portion remains closed. 100 In this way, heated air can be readily directed downwardly through the flue portion 16 onto the burning material in the fire box to increase combustion, or air may be directed upwardly through the flue portion 15 105 to the smoke pipe 10 to thereby decrease or check the draft through the stove. Also, as noted, the valve may be positioned to cut off the flow of air entirely from the flue casing. 110

Obviously, the parts of the improved draft attachment can be economically manufactured and readily assembled. The details set forth can be varied without departure 5 from the essentials of the invention as defined in the claims.

I claim as my invention:—

1. In a draft attachment for stoves, the combination of the stove casing, a straight 10 flue casing of substantially uniform U-shape in cross section secured in vertical position to the inner face of said stove casing, said flue casing being divided into upper and lower portions arranged in vertical alignment 15 and having outlets opening respectively into the smoke pipe and the combustion chamber at a point above the fire, said stove casing having a common air inlet for said flue portions, and a valve arranged 20 within said flue casing and having means for closing either or both of said flue portions and for controlling the admission of air from said common air inlet to one or the other of said flue portions, substantially as 25 described.

2. In a draft attachment for stoves, the combination of a stove casing, a vertically disposed, open-ended flue casing arranged 30 on one side of said stove casing, and a shift- able valve member dividing said casing into upper and lower flue portions adapted to deliver air to the smoke pipe or to the combustion chamber at a point above the fire, said valve member being arranged to con- 35 trol the admission of air to one or the other of said flue portions, substantially as de- scribed.

3. In a draft attachment for stoves, the combination of a stove casing having an air 40 inlet, a flue casing of U-shaped cross section secured to the inner face of the stove casing over said air inlet, and a common valve member dividing said flue casing into sep- 45 arate flue portions extending upwardly and downwardly from said air inlet and adapted to deliver air to the smoke pipe or to the combustion chamber at a point above the fire, said valve member being arranged to close either or both of said flue portions or control 50 the admission of air from said inlet to one or the other of said flue portions, substan- tially as described.

4. In a draft attachment for stoves, the combination of the stove casing, a vertically disposed flue casing arranged within and 55 on one side of the stove casing, said flue casing being divided into upper and lower portions having a common air inlet and sep- arate outlets opening respectively into the smoke pipe and the combustion chamber at 60 a point above the fire, and a cylindrical valve arranged within said valve casing and having an open outer end communicating with said air inlet and said cylindrical valve having a peripheral wall for closing either 65 or both of said flue portions and provided with a port adapted to register with one or the other of said flue portions for placing the same in communication with said com- mon air inlet, substantially as described. 70

5. In a draft attachment for stoves, the combination of the stove casing having an air inlet, a substantially vertical flue casing of U-shaped cross section secured to the inner face of the stove casing over said air 75 inlet, said valve casing having outlets at its ends opening respectively into the smoke pipe and the combustion chamber at a point above the fire, and a rotatable, cylindrical valve fitting within said flue casing, com- 80 municating at its outer end with said air inlet and having means for cutting off the flow of air through said flue casing or for directing the air either upwardly or down- wardly therethrough, substantially as de- 85 scribed.

6. In a draft attachment for stoves, the combination of the stove casing having an air inlet, a substantially vertical flue casing of U-shaped cross-section secured to the 90 inner face of the stove casing over said air inlet, said valve casing having outlets at its ends opening respectively into the smoke pipe and the combustion chamber at a point above the fire, and a rotatable, cylindrical valve open at its outer end and extending through said air inlet into said flue casing to divide the latter into upper and lower flue 95 portions, said valve having means for closing either or both of said flue portions and 100 for controlling the flow of air through either portion, substantially as described.

JAMES H. DEAN.
